UNITED STATES PATENT OFFICE

LESTER L. JONES, OF ORADELL, NEW JERSEY

UNI-CONTROL APPARATUS

Application filed October 2, 1926. Serial No. 139,086.

This invention relates to a uni-control adjusting apparatus, and more particularly to a uni-control apparatus for controlling independently operable adjustable units both simultaneously and independently; and has special reference to a uni-control apparatus especially adapted for controlling the adjustable tuning units of a radio receiving set.

10 A prime object of my present invention centers about the provision of a control apparatus for radio receiving sets operable by means of a single control element and constructed and designed for mechanically 15 coupling the tuning units of the set for simultaneous adjustment and for mechanically uncoupling the tuning units to permit independent adjustment of the units.

In tuned radio receiving systems having 20 one or more steps of radio frequency amplification, there are provided a number of units such as condensers or inductance devices which are independently adjustable for tuning the cascaded circuits of the system 25 to a given frequency or wave length; and when a plurality of steps of radio frequency amplification are employed, there are provided three or more such units which have to be independently adjusted by operating 30 three or more dials for tuning the set. This method of tuning is disadvantageous, and for rapid and convenient tuning of the set it is highly desirable to simultaneously 35 adjust and operate all the units from a single control dial or handle.

These tuned radio receiving systems are usually designed and constructed so that each of the tuning elements may be adjusted in like manner practically degree for degree over the whole wave length range, rendering possible simultaneous adjustment of all the units. In highly selective or/and sharply tuned circuits, however, it has been found extremely difficult to match the tuning units or/and the cascaded circuits there- 45 of to the high degree of precision necessary for producing sharp tuning or high selectivity; and in such circuits it has been found desirable to provide mechanism for permitting the independent adjustment of the tun-

ing units for sensitive and accurate tuning purposes after approximate settings of the units are produced by simultaneous adjustment thereof. The provision of an improved apparatus constructed for mechanically coupling and uncoupling the tuning units to permit of this simultaneous and independent operation of the same is a prime object of my present invention.

A further prime object of my present invention centers about the provision of a uni-control apparatus for accomplishing the simultaneous and independent adjustment of the tuning units which is characterized by the use of a single control element operable for effecting the coupling between the tuning units and for effecting the disconnection or decoupling thereof. A correlative object of the invention relates to the provision of a uni-control apparatus of this character in which the said single control element is mounted so as to be axially shiftable or reciprocable for effecting the coupling and decoupling functions.

When a given approximate or accurate setting of the dials has been obtained, it is highly desirable, when the mechanical coupling or uncoupling of the tuning elements is effected, to prevent or minimize any disturbance to or modification of the setting already produced. It is therefore a further prime object of the invention to provide a control mechanism of the nature referred to in which the units may be linked and unlinked with a minimum disturbance or change of any previous setting obtained.

An important problem in the design of a serviceable and efficient uni-control apparatus is that of linking or coupling the tuning units together in such manner that when the same are unlinked or disconnected for independent tuning purposes, the tuning elements or circuits of which they form a part should not be accidentally thrown or misadjusted so far out of tune one relative to the other as to prevent any signal being heard, or in other words, to prevent any such relative displacement between the tuning elements as to render it difficult to bring these tuning elements back into correspond-

ing positions. This problem is especially acute where only a single control dial is employed and where all of the shafts of the tuning units are within and concealed by the radio casing or cabinet. It is therefore a further principal object of my present invention to so design and construct the uni-control apparatus as to prevent more than a given displacement of one adjustable unit relative to another adjustable unit so that at all times the tuning of the set may be under the control of the operator.

To the accomplishment of the foregoing and such other objects as will hereinafter appear, my invention consists in the elements and their relation one to the other, as hereinafter more particularly described and sought to be defined in the claims; reference being had to the accompanying drawings which show the preferred embodiment of my invention, and in which:

Fig. 1 is an elevational view of the uni-control apparatus embodying the principles of my present invention and showing some of the parts in cross-section.

Fig. 2 is a view thereof taken in cross-section in the plane of the line 2—2, Fig. 1, and

Fig. 3 is a view thereof taken in cross-section in the plane of the line 3—3, Fig. 1.

Referring now more in detail to the drawings, the uni-control apparatus of my invention comprises in its broad aspects, in combination, a plurality of independently adjustable units generally designated as A and A' and an operating means therefor generally designated as B mechanically connectable to the plurality of adjustable units for operating the same in unison and mechanically disconnectable from one or either of said adjustable units for independently operating the other of the adjustable units.

The independently adjustable units A and A' may comprise any suitable apparatus, and when my invention is employed in connection with radio receiving circuits, the same may comprise tuning condensers mounted on a base support 10 by any suitable means such as the angle brackets 11, 11, each of the condensers being mounted in the framework embodying end plates 12, 12 secured together by connecting rods 13, 13, the adjustable element or rotor of the condenser being represented by the rotor shafts 14, 14 journalled in the end plates 12, 12 in any conventional manner, the said rotor shafts having extensions 14' and 14² mechanically dissociated so as to be capable of independent adjustment and connectable in the manner to be described hereinafter to the operating means B for accomplishing the selective simultaneous and independent adjustment of the units.

The operating means B comprises a driving mechanism b mechanically connectable

to the shafts of the plurality of tuning units A and A' and mechanically disconnectable from one or either of said shafts and a single control element or shaft b' connected to the driving means B for producing the operations thereof.

In the preferred construction to accomplish all of the objects hereinabove referred to, the driving means b of the operating means B comprises clutch elements 15' and 15² fixed respectively by means of the collars 16' and 16² to the shafts 14' and 14² of the adjustable units, and sets of complementary clutch elements, one set for each of the clutch disks 15' and 15² carried by a driving pulley 17, one set of complementary clutch elements comprising the resilient members 18', 18² carried in cups 19', 19² fixed to elongated bearings 20', 20² each mounted for free slideable movement on the rods 21', 21², both rods being fixedly carried by the drive pulley 17, the other set of complementary clutch elements comprising the clutch members 22', 22² carried in cups 23', 23² mounted on the elongated bearing elements 24', 24² also mounted for free sliding movement on opposite ends of the rods 21', 21². All of the clutch elements are held in cooperative relation as shown in Fig. 1 of the drawings by means of the expansion springs 25', 25² seated between the cups 19' and drive pulley 17 and similar springs 26', 26² seated between the cups 23' and the driving pulley 17.

The single control element for shaft b' comprises a shaft element mounted for slideable or reciprocable movement in bracket supports 27, 27 fixed to the condenser frame, the said shaft having a control handle (not shown) fixed to the extending end 28' of the control shaft 28, the said shaft being axially shiftable to a plurality of determinable positions, said positions being determined by means of a spring-pressed ball bearing means 29, the ball bearing 30 of which works in circular notches 31, 31 provided in the shaft 28. The shaft 28 is further provided with a pulley 32 fixed to the shaft, which pulley is connected to the drive pulley 17 by means of a cord 33 which may be wound once around the pulley 17 and a number of times around the pulley 32, the said cord being preferably kept taut by means of a spring 34 (see Fig. 2) connecting the ends of the cord. The design and relative dimensions of the pulleys 17 and 32 are such as to produce a motion-reducing operation; and the flexible and yieldable connection between the two pulleys is such as to permit rotational operation of the pulley 17 by reduced motion without introducing any undesirable stresses or strains therein.

For moving the driving means b to effect the coupling and decoupling operations of

the adjustable units A and A', the pulley 32 on the single control shaft b' is provided with the flanges 32', 32' which straddle the drive pulley 17, as clearly shown in Fig. 1 of the drawings, so that the axial shifting of the shaft 28 of the single control element produces an axial shifting of the drive pulley 17. This drive pulley 17 is provided with a central hub portion 17' which freely receives at its opposite ends the shafts 14' and 14² of the tuning units for relative supporting purposes. The axial movements imparted to the drive pulley 17 effect the selective coupling and decoupling connections between the operating means and the shafts of the tuning units by operating in a selective manner the sets of complementary clutch elements 18' and 22'; and this is accomplished by the provision of the sets of terminal screw elements 35', 35' and 35², 35² threaded to the ends of the rods 21', 21', the heads of these screw elements being adapted to engage the outward ends of the elongated clutch bearings 20', 20' and 24', 24' when these rods and the drive pulley 17 to which they are fixedly attached are moved in one or the other direction.

With the last-recited construction it will be seen that with the parts in the position shown in Fig. 1 of the drawings, the sets of complementary clutch elements 18', 18' and 22', 22', are in engagement with the clutch disks 15' and 15² so that rotation of the uni-control shaft 28 produces a simultaneous adjustment of the tuning units A and A'. When, however, the shaft 28 is shifted one notch to the right viewing the same from Fig. 1, the drive pulley 17 is correspondingly shifted and the screw heads 35', 35' engage the ends of the clutch element bearings 20', 20' and effect the declutching of complementary clutch elements 18', 18' from the clutch disk 15'; and with the parts in this position the tuning unit A' may be adjusted independent of the tuning unit A by rotation of the control shaft 28, since in this position the clutch elements 22' and 15² are in connecting or clutching engagement. For adjusting the tuning unit A independently of the tuning unit A' should such adjustment be desired, the control shaft 28 is moved one notch to the left from the position shown in Fig. 1, such movement effecting the disengagement of the complementary clutch elements 22', 22' from the clutch disk 15², freeing or uncoupling the shaft 14² of the tuning unit A'. In this manner axial shifting of a single control shaft may be employed for producing a simultaneous tuning or adjustment of the units or an independent tuning or adjustment of either one of the units.

With this described construction it will furthermore be seen that after producing an independent adjustment subsequent to a si-

multaneous adjustment of the units, the parts may be returned to the position shown in Fig. 1, of the drawings, where all the parts are coupled together, without vitiating any prior adjustment or setting, since the movement of the driving means b in axial directions with the consequent clutching and declutching operations produces no tendency to a rotative motion of the tuning units which would disturb any prior setting obtained. The parts are, moreover, constructed so that any longitudinal or axial stresses produced are insufficient to disturb the prior setting arrived at.

As heretofore mentioned, it is a further object of my present invention to so design and construct the uni-control apparatus as to prevent more than a given displacement of one adjustable unit relative to another adjustable unit, this so as to obviate an accidental throwing of one unit so far out of tune relative to another unit as to prevent any signal being heard. This I accomplish by the provision of means for limiting the relative motion between the driving parts of the operating means b and the tuning unit from which the driving means is disconnected at any time. In the preferred construction this motion limiting means comprises arcuate slots 36', 36' in the clutch disk 15' and similar slots 37', 37' in the clutch disk 15², through which slots the clutch bearings 20', 20' and 24', 24' respectively project, the ends of the slots cooperating with the rod ends of the clutch bearings to limit the rotative motion of the driving means b relative to either of the clutch disks 15' or 15² when the driving means is declutched therefrom. In this way neither of the tuning units can be displaced from the other to an extent which will prevent the signal being heard, and by this means I am therefore enabled to have the tuning units always under the control of the operator, the same being rendered "fool proof", although such tuning units are capable of the simultaneous coarse adjustment and the independent fine adjustments desired.

The manner of making, using and operating the uni-control system of my present invention and the many advantages thereof will in the main be fully apparent from the above detailed description thereof. It will be further apparent that while I have shown and described my invention in the preferred form, that many changes and modifications may be made in the structure disclosed without departing from the spirit of the invention, defined in the following claims.

I claim:

1. A uni-control radio apparatus comprising, in combination, a plurality of independently adjustable tuning units, an operating means therefor mechanically connectable to the plurality of adjustable units for

- operating the same in unison and mechanically disconnectable from one of said adjustable units for independently operating the other of the adjustable units, and a single control shaft connected to the operating means for moving the same, the said control shaft being axially shiftable to effect the said connection of the operating means with and disconnection of the same from the said adjustable units.
2. A uni-control radio apparatus comprising, in combination, a plurality of axially alined adjustable tuning units, an operating means therefor mechanically connectable to the plurality of adjustable units for operating the same in unison and mechanically disconnectable from one of said adjustable units for independently operating the other of the adjustable units, said operating means including a motion reducing mechanism and a single control shaft, the said control shaft being movable to effect the said connection of the operating means with and disconnection of the same from the said adjustable units.
3. A uni-control apparatus comprising, in combination, a plurality of independently adjustable units having axially alined mechanically disconnected shafts, an operating means therefor mechanically connectable to the plurality of alined shafts for operating the same in unison and mechanically disconnectable from either of said shafts for independently operating the other of the said shafts, and a single control shaft connected to the operating means for moving the same, the said control shaft being axially shiftable to effect the said connection of the operating means with and disconnection of the same from the said adjustable shafts.
4. A uni-control apparatus comprising, in combination, a plurality of independently adjustable units, an operating means therefor mechanically connectable to the plurality of adjustable units for operating the same in unison and mechanically disconnectable from one of said adjustable units for independently operating the other of the adjustable units, means for limiting the relative motion between the operating means and the disconnected unit to prevent more than a given displacement of one adjustable unit relative to the other adjustable unit, said operating means including a single control element movable to effect the connection of the operating means with and the disconnection of the same from the said adjustable units.
5. A uni-control apparatus comprising, in combination, a plurality of independently adjustable units, an operating means therefor mechanically connectable to the plurality of adjustable units for operating the same in unison and mechanically disconnectable from either of said adjustable units for independently operating the other of the adjustable units, said operating means comprising units for independently operating the other of the adjustable units, means for limiting the relative motion between the operating means and either of the disconnected units to prevent more than a given displacement of one adjustable unit relative to the other adjustable unit, said operating means including a single control element movable to effect the connection of the operating means with and the disconnection of the same from the said adjustable units.
6. A uni-control apparatus comprising, in combination, a plurality of independently adjustable units, an operating means therefor having clutch elements mechanically connectable to the plurality of adjustable units for operating the same in unison and mechanically disconnectable from one of said adjustable units for independently operating the other of the adjustable units, means for limiting relative rotative motion between the operating means and the disconnected unit to prevent more than a given displacement of one adjustable unit relative to the other adjustable unit, said operating means including a motion reducing mechanism and a single control shaft axially movable to effect the connection of the operating means with and the disconnection of the same from the said adjustable units.
7. A uni-control apparatus comprising, in combination, a plurality of independently adjustable units and an operating means therefor mechanically connectable to the plurality of adjustable units for operating the same in unison and mechanically disconnectable from one of said adjustable units for independently operating the other of the adjustable units, said operating means comprising a clutch element fixed to the shaft of one of the adjustable units, a complemental clutch element, means connecting the complemental clutch element to another of the adjustable units, a single control shaft, and motion reducing mechanism connecting the single control shaft with the complemental clutch element movable by movement of said control shaft for operating the clutch elements.
8. A uni-control apparatus comprising, in combination, a plurality of independently adjustable units and an operating means therefor mechanically connectable to the plurality of adjustable units for operating the same in unison and mechanically disconnectable from either of said adjustable units for independently operating the other of the adjustable units, said operating means comprising a clutch element fixed to the shaft of each of the adjustable units, complemental clutch elements for each of the shaft clutch elements, a single control shaft, and mechanism connecting the single control shaft with the complemental clutch elements movable by movement of said control

shaft for selectively operating the clutch elements.

9. A uni-control apparatus comprising, in combination, a plurality of independently adjustable units and an operating means therefor mechanically connectable to the plurality of adjustable units for operating the same in unison and mechanically disconnectable from one of said adjustable units for independently operating the other of the adjustable units, said operating means comprising a clutch element fixed to the shaft of one of the adjustable units, a complementary clutch element, a single control shaft, mechanism connecting the single control shaft with the complementary clutch element movable by movement of said control shaft for operating the clutch elements, and means for limiting relative rotational motion between the clutch elements to prevent more than a given displacement of one adjustable unit relative to the other adjustable unit.

10. A uni-control apparatus comprising, in combination, a plurality of independently adjustable units and an operating means therefor mechanically connectable to the plurality of adjustable units for operating the same in unison and mechanically disconnectable from one of said adjustable units for independently operating the other of the adjustable units, said operating means comprising a clutch element fixed to the shaft of one of the adjustable units, a complementary clutch element means connecting the complementary clutch element to another of the adjustable units, a single control shaft mechanism connecting the single control shaft with the complementary clutch element movable by movement of said control shaft for operating the clutch elements, and means for limiting relative rotational motion between the clutch elements to prevent more than a given displacement of one adjustable unit relative to the other adjustable unit, said motion limiting means comprising a slot in the shaft clutch element and a rod carried by the complementary clutch element movable in said slot.

11. A uni-control apparatus comprising, in combination, a plurality of independently adjustable units and an operating means therefor mechanically connectable to the plurality of adjustable units for operating the same in unison and mechanically disconnectable from either of said adjustable units for independently operating the other of the adjustable units, said operating means comprising a clutch element fixed to the shaft of each of the adjustable units, complementary clutch elements for each of the shaft clutch elements, a single control shaft, mechanism connecting the single control shaft with the complementary clutch elements movable by movement of said control

shaft for selectively operating the clutch elements, and means for limiting relative motion between the complementary clutch elements of each unit to prevent more than a given displacement of one adjustable unit relative to the other adjustable unit.

12. A uni-control apparatus comprising, in combination, a plurality of independently adjustable units and an operating means therefor mechanically connectable to the plurality of adjustable units for operating the same in unison and mechanically disconnectable from either of said adjustable units for independently operating the other of the adjustable units, said operating means comprising a clutch element fixed to the shaft of each of the adjustable units, complementary clutch elements for each of the shaft clutch elements, a single control shaft, motion reducing mechanism connecting the single control shaft with the complementary clutch elements movable by movement of said control shaft for selectively operating the clutch elements, and means for limiting relative motion between the complementary clutch elements of each unit to prevent more than a given displacement of one adjustable unit relative to the other adjustable unit.

Signed at New York City, in the county of New York and State of New York this 30th day of September, A. D. 1926.
